UNITED STATES PATENT OFFICE.

ERIC G. BJORKLUND, OF BRIDGEPORT, CONNECTICUT.

SMOKING PIPE.

Application filed December 6, 1922. Serial No. 605,175.

To all whom it may concern:

Be it known that I, ERIC G. BJORKLUND, a citizen of the United States, residing at Bridgeport, county of Fairfield, State of Connecticut, have invented an Improvement in Smoking Pipes, of which the following is a specification.

This invention relates to a tobacco pipe and has for an object to provide an improved pipe which will give a cool, clean smoke, and which may be easily cleaned. It is also an object of the invention to provide a pipe in which there is little chance for the nicotine and moisture which gathers in the pipe to get into the smoke passage in the stem even should the pipe be turned on its side.

With the foregoing and other objects in view, I have devised the construction illustrated in the accompanying drawing, in which—

Fig. 1 is a top plan view of one type of pipe embodying my invention.

Fig. 2 is a partial side elevation and partial sectional view thereof.

Fig. 3 is a side elevation of the bowl removed from the pipe.

Fig. 4 is a view similar to Fig. 2 showing my invention as applied to a different type of pipe.

Fig. 5 is a side elevation thereof looking from the right of Fig. 4, and with the mouth piece removed.

Fig. 6 is a top plan view of a flange member adapted for insertion in the body of the pipe.

Fig. 7 is a partial side elevation and partial side view of the same, and

Fig. 8 is a partial section and partial side elevation of the lower portion of the pipe shown in Fig. 4 indicating how a cleaning opening may be applied thereto.

Referring to Figs. 1, 2 and 3 the body of the pipe is indicated at 10 which is hollow and open at the top to receive the open bowl 11. This bowl is provided with means for securing it in the body member and with its outer side walls spaced from the inner side walls of the body to provide a smoke passage 12. The bowl is preferably provided at its upper end with an outwardly extending knurled flange 13 of substantially the same diameter as the body, so that when the bowl is in position in the body the outer surface of the pipe will be continuous; and the bowl has threaded engagement with the

body immediately under this flange, as shown at 14. Adjacent the lower end of the bowl preferably in the bottom thereof are one or more outlet openings 15. The body has connected therewith a stem 16 having the usual mouth piece 17 and a smoke passage 18 which leads from the smoke passage 12 at the upper part thereof. Within the smoke passage 12, preferably extending outwardly from the outer wall of the bowl, and between the bottom of the bowl and the smoke passage 18 is a downwardly inclined flange 19 extending around the bowl and spaced a short distance from the inner wall of the body. This flange acts as a baffle for the smoke and also collects and holds moisture which runs down the outside of the bowl allowing it to drip off the edge of this flange.

Within the body of the pipe and below the bottom of the bowl is a moisture and nicotine chamber 20 and between the bottom of this chamber and the bottom of the bowl and leading downwardly and inwardly from the inner walls of the body, is a flange 21 providing an opening 22 leading to this chamber, and as this flange is downwardly inclined it provides an annular pocket 23 beneath the same. The body may be closed at its lower end but I prefer to make it open and close it by means of a suitable cap or plug 24 having threaded engagement with the body, as shown at 25, the plug or cap being preferably substantially of the same diameter as the body to form a continuous surface. The body portion and the stem may be made of any suitable material desired as may also the bowl, but I prefer to make the bowl of suitable wood such as briar to give the woody taste so much desired.

In operation the tobacco is placed in the bowl in the usual manner and the smoke will be drawn through the openings 15 and passage 12 to the stem around the outside of the bowl. The flange 19 keeps moisture from gathering on the body of the bowl as any moisture which gets on to the outer walls thereof will collect on the edge of this flange and drop off onto the inner walls of the body. This moisture as well as other moisture from the stem will run down the flange 21, through the opening 22 and into the chamber 20 where it will be retained. Should the pipe be laid on its side or turned

upside down the moisture which has collected in the chamber 20 will be held in the groove or pocket 23 beneath the flange 21, and so there is no opportunity for it to get into the stem or through the smoke openings 15 in the bowl to the tobacco, thus providing at all times a clean, cool smoke.

Even though the removable cap 24 is not provided the pipe may be easily and thoroughly cleaned by removing the bowl, but the use of a removable cap such as shown at 24 naturally facilitates cleaning of the walls of the chamber 20.

In Figs. 5 to 8 I have shown a slightly different construction and also a different type of pipe. In this pipe the body 26 is open at its upper end and threaded on the inner walls thereof, as shown at 27, to receive an open bowl 28 similar to that shown in Figs. 1 to 3, which has a knurled flange 29 and is threaded beneath the same to engage the threads in the body. This bowl also has smoke-out openings 30 and a downwardly and outwardly directed flange 31 on its outer wall extending into the smoke passage 32 between the bowl and the body. Around the lower edge of the bowl I prefer to provide a downwardly extending flange 33 which also acts as a means to gather moisture and causes it to drip from the bowl to prevent its getting into the smoke openings 30 and into the bowl. Within the body and beneath the bowl is a moisture and nicotine chamber 34 and between the bottom of this chamber and the bottom of the bowl is a flange 35 leading inwardly and downwardly from the side walls of the body to an opening 36, corresponding to the flange 21 of the first form. This flange, however, instead of being integral with the body, is preferably a piece of resilient metal having a downwardly extending flange 37 slit at certain points as 38 to provide resilient means for engaging the inner walls of the body member to retain the flange in position therein. The body has an upwardly inclined stem 39 with a smoke passage 40 leading from the upper part of the smoke passage 32, and connected with this stem is the usual upwardly extending curved mouth piece 41. As the stem extends from the upper part of the body I preferably close the space beneath the same and the bottom of the body to give a neat appearance and continuous effect by means of a rib 42.

In operation this pipe is practically the same as the first form, the flange 31 having the same effect as the flange 19 in the first form, while the flange 33 provides an additional protection from moisture to the tobacco in the bowl as pointed out above. The flange 35 being removable, by removing the bowl and this flange it will be apparent the inner continuous walls of the body may

be easily and thoroughly cleaned. Thus with this pipe no removable plug is required in the lower part of the body, but a removable plug, such as shown at 43 in Fig. 8 may be provided if desired. As in the first form various portions of the pipe may be made of different materials as desired, but I prefer to make the bowl of wood as in the first form. The removable flange 35 through the downwardly tapered flange 37, has a tight connection with the inner wall of the body and so provides a pocket or groove 44 beneath the same, corresponding to the pocket 23 beneath the flange 21 in the first form. This flange and pocket, similar to the flange and pocket in the first form, retains the moisture collected in the chamber 34 should the pipe be laid on its side or turned upside down, and prevents it from passing to the stem or the tobacco in the bowl.

Having thus set forth the nature of my invention, what I claim is:

1. A pipe comprising a hollow body, an open bowl in said body and located at a distance from the side walls thereof to provide a space between the bowl and body, said bowl being provided with one or more smoke outlets in the lower part thereof, a downwardly and outwardly extending flange on the outer wall of the bowl in said space and above said outlets, and a stem having a smoke passage leading from said space above said flange.

2. A pipe comprising a hollow body, an open bowl in said body provided with a smoke outlet in the lower part thereof, said bowl being spaced from said body to provide a smoke passage between them, a stem having a smoke passage leading from the first passage above the bottom of the bowl, and a downwardly extending flange on the outer walls of the bowl located between the outlet from the bowl and the entrance to the passage in the stem.

3. A pipe comprising a hollow body, an open bowl in said body and spaced therefrom to form a smoke passage about the bowl and a chamber beneath the bowl, said bowl being provided with smoke outlet passages in the lower part thereof, a downwardly and inwardly extending imperforate annular flange carried by the body in said chamber beneath the bowl to provide an inverted annular receptacle, a downwardly extending annular flange projecting from the bowl into the smoke passage above the outlet passages from the bowl, and a stem having a smoke passage leading from the first passage above said flange.

4. A pipe comprising a hollow body, an open bowl in said body and spaced therefrom to form a smoke passage about the bowl and a chamber beneath the bowl, said bowl being provided with a smoke outlet

passage in the bottom thereof, an inwardly and downwardly extending imperforate flange leading from the wall of the body beneath the bowl and above the bottom of the body to provide an inverted annular receptacle, a stem provided with a smoke passage leading from the space between the

body and the bowl above said flange, and a downwardly extending flange on the outer walls of the bowl located between the smoke outlet passage in the bowl and the entrance to the smoke passage in the stem.

In testimony whereof I affix my signature.
ERIC G. BJORKLUND.
